UNITED STATES PATENT OFFICE.

CHRISTIAN N. SMITH, OF ELGIN, ILLINOIS, ASSIGNOR OF ONE-HALF TO WILLIAM P. TOPPING, OF ELGIN, ILLINOIS; ALICE MINNIE SMITH AND LILY IRENE SMITH EXECUTRICES OF SAID CHRISTIAN N. SMITH, DECEASED.

MACHINE FOR HEATING AND BENDING METALLIC PRINTING PLATES, SUCH AS ELECTROTYPE AND STEREOYPE PLATES.

Application filed May 5, 1924. Serial No. 711,297.

This invention relates to that class of machines for heating and bending metallic printing plates, whereby metallic printing plates, such as electrotype and stereotype plates may be heated and bent into suitably curved form for use in printing.

The principal object of the invention is to provide a simple, economical and efficient machine for heating and bending metallic printing plates, such as electrotype or stereotype plates.

Other and further objects of the invention will appear from the following description and claims, and from an inspection of the accompanying drawings, which are made a part of this specification.

The invention consists in the features, combinations, details of construction and arrangement of parts, herein described and claimed.

In the accompanying drawings—

Figure 1 is a view in front elevation of a printing-plate bending machine constructed in accordance with my invention, and adapted to be used for heating and bending metallic printing plates in accordance with my improved process or otherwise as desired, the hollow heating roll being shown in vertical section;

Fig. 2 is a view in side elevation of the machine shown in Fig. 1, with parts broken away and the driving worm and worm wheel and their supports omitted for clearness of illustration;

Fig. 3 is a detail view in perspective of a hollow heating and bending roll, with a metallic printing plate, compressible matrix-forming sheet material, flexible outer and intermediate metallic plates, and intermediate sheets of compressible material between the outer metallic backing plate and intermediate metallic sheet as well as between the intermediate metallic sheet and the metallic printing plate to be operated on such as are also shown between the bending rolls in Fig.

1, in position upon the hollow heating and bending roll of my improved bending machine; and

Fig. 4 is a detail view in side elevation showing the perforated end portions of the hollow heating and bending roll, and means

for opening and closing or controlling the gas and air inlets to the interior of the heating roll or combustion chamber.

In constructing a machine for heating and bending metallic printing plates, such as electrotype and stereotype plates, in accordance with my invention, I provide a main frame 1, which may be of any desired ordinary and well known or suitable form adapted to support the working parts of the machine. The frame shown in the drawings is provided with upright side frame members 2 and 3 fixed to and extending upward from a bed or table 4 which has legs 5 of suitable size and strength to form a strong and rigid support for the bed or table. Suitable uprights or standards 6 and 7 are fixed to and extend upward from the bed in position to support a driving shaft 8 which is journaled in suitable bearings 9, in said standards 6 and 7. Fixed to the rotative main driving shaft 8 is a gear or worm wheel 10 which may be of any desired well known or suitable form of gear wheel or driving means adapted to be connected with a suitable source of power. And suitable clutch mechanism of any desired ordinary and well known or suitable form, not shown, may be provided for connecting and disconnecting the shaft 8 or wheel 10 with the source of power or with each other. In the form of the device here shown, however, the gear 10 is a worm wheel fixed to the shaft 8 and in toothed engagement with a worm or screw 11 which is fixed to a worm shaft 12 journaled in suitable bearings 13 on a frame member or standard 14. The worm wheel 10 and worm 11 are thus located between the standards 6 and 7 which rotatively support the driving shaft 8 in position to be connected with and disconnected from the hollow heating and bending roll or rolls of any desired or various dimensions to be operated.

Removably mounted and journaled in suitable bearings in the standards or frame members 2 and 3 is a hollow heating and bending roll 15 having a curved or cylindrical outer wall 16, end walls 17 and 18, hollow hubs or journals or axle members 19, 20, and end flanges, plates or hub members

21, 22. The end wall or head 17 at one end of the roll 15 is removably mounted in the end of the cylindrical or outer peripheral wall of the heating and bending roll which 5 is provided with a suitable annular recess, annular flange 24 and shoulder 25 for engaging and removably holding the said head in place in the end of the roll.

The standards 2 and 3 are each provided 10 with a recess or slot 26 having marginal walls 27, 28 adapted to admit the axle or corresponding end journals 19, 20 therebetween. And suitable removable bearing blocks or journal bearings 29, 29 are, by 15 preference provided and each mounted in a corresponding slot or recessed portion 26 in the frame, and are adapted to removably support the heating roll or rolls in operative position in the frame.

20 Suitable means are provided for detachably connecting the removable hollow heating and bending roll or rolls with the driving shaft 8 or other driving means, in such a manner that the roll or rolls may be removed and replaced without disturbing the driving mechanism and without employing a worm wheel or gear wheel for each roll, and so as to enable heating and bending rolls of different diameters or sizes to be 25 used interchangeably and detachably connected with facility successively and interchangeably in any desired order with the driving mechanism. And although any suitable ordinary and well known form of connecting means or clutch mechanism may be 30 employed which is adapted to suitably detachably connect the axle or journal of the heating roll or rolls with the driving shaft may be employed, I have here shown a very 35 simple and efficient clutch mechanism or connecting means for accomplishing this purpose.

Each hollow heating and bending roll 15 is provided with one or more perforations 45 or recesses 30 in the hub or end plate 22 of such roll or rolls. And one or more bosses, pins, or equivalent connecting members 31 is or are provided and adapted to engage such recess or recesses or equivalent connecting means, so as to removably and detachably connect the roll or rolls with the driving shaft. In the form of clutch or connecting and disconnecting means here shown, a head or plate 32 is fixed to the shaft 8 and provided with a perforation 33 for each pin 31, each of said pins being adapted to be moved endwise into and out of an adjacent or corresponding recess or perforation 30 in the end member or flange 50 55 60 65 70 75 80 85 90 95 100 105 110 115 120 125 130 135 140 145 150 155 160 a movable clutch member or ring 34 is provided and mounted in position to encircle and to be readily moved longitudinally of the shaft 8, said clutch member being, by preference, annular and provided with an 70 annular peripheral groove 35 in operative engagement with which the forked arms 36 of a clutch-operating lever or yoke 37 are mounted. This lever or yoke is supported by means of a bracket arm 38 or other suitable supporting means, mounted in a suitable support, such, for example, as the standard 3; the lever being connected with the fixed support by means of a pivot pin 39 or other suitable means. Means are provided for heating the hollow heating and bending roll or rolls, which may be of different or varying sizes, and are interchangeable, and whereby printing plates may be heated and bent to any desired curvature corresponding with the curvature of the roll employed. Each heating and bending roll 15 forms an inner heating or combustion chamber 40. Each roll has an axial opening 41, which, by preference extends through one of the journals or hubs and the corresponding end wall of the roll, for example, through hub 19 and end wall 17 already described. A fuel supply conduit is provided which 95 communicates with a source of gas or hydrocarbon fuel supply and with the burner located inside of or in position to heat the heating or combustion chamber formed by the roll. The fuel supply conduit consists of or comprises, by preference, a gas or hydrocarbon fuel supply pipe 42 which communicates with the source of fuel supply or gas supply, a conduit or pipe 42' which extends into or through the axial opening 41 and has a cup 43' on or, by preference, detachably connected with the outer end of said pipe 42' into which the inner end of the pipe projects.

The pipe 42 is, by preference, detached from pipe 42' and roll 15; and the usual air inlet leads into the fuel passage thus formed. Pipe 42' is connected with the burner parts inside the roll which are in the form of one or more branch pipes 44 each communicating with the inner extremity of the supply pipe 42', or may consist of an extension of said supply pipe located in the combustion chamber or inner heating chamber formed by the hollow roll. In the form of the device shown in the drawings, a plurality of branch pipes 44 are provided, each having a perforated portion 45 located inside of the hollow roll and near the periphery or outer plate-engaging and bending wall 16 of the roll and connected and communicating with the pipe 42' and the fuel supply passage formed thereby. These perforated pipe portions, of which there may be one or any desired number, ex-

tend parallel to the axis of the hollow roll on the interior of which the burner thus formed by the perforated pipe or pipes is located. Each pipe 45 is provided with a series of suitable perforations 46 through its peripheral wall; and the perforated pipe or pipes and the series of perforations therein extend from end to end of the hollow roll inside of and near the periphery of the combustion chamber formed by or inside of the roll.

The combustion chamber 40, inside of the hollow roll, is by preference annular, and is adapted to permit or cause the heat generated within the roll and the combustion chamber formed thereby, to be provided at or near the periphery of the roll, so as to enable the periphery of the roll and particularly that portion of the peripheral wall of the roll which is in heating and bending engagement with the metallic printing plate to be operated upon, to be heated uniformly to the desired or required degree of heat necessary to enable the metallic printing plate, such as an electrotype or stereotype plate, to be bent uniformly and accurately to the desired predetermined degree of curvature, corresponding with the curvature of the peripheral wall portion of the roll which is in engagement with and which acts to heat and bend the metallic printing plate.

The hollow heating and bending rolls 15—of which there may be any desired number of varying sizes or different diameters adapted to be used interchangeably as aforesaid—are each provided with an inner wall or hollow drum 47 which is by preference approximately cylindrical and comprises an annular wall which may be made in one integral piece with the outer end wall of the roll, either end wall 19 or end wall 18, or integral with either one or other of the hubs of the roll 15. A very satisfactory construction of the inner liner or inner drum members, however is shown in the drawings, and comprises a hollow cylindrical or annular drum 47 of sheet metal of less diameter than and spaced apart from the peripheral outer wall of the hollow roll and extending from end to end of the roll on the inside thereof in position to encircle the longitudinal axis of the roll and form an inner partition wall between the outer wall and the axis of the hollow heating roll. At one end of the drum 47 is provided an inner end wall 48 which may be integral with the inner drum 47; but for convenience and economy in construction the inner end wall 48 is made in a separate piece of sheet metal and provided with an inner annular marginal flange 49 which is fitted snugly in engagement with the adjacent end of the drum 47. And a similar end wall 50 is mounted on the inside of the roll and in snugly fitting engagement with the opposite end of the drum 47, of which it may form

an integral part if desired, although it is by preference bent to form an annular flange or shoulder 51 which fits snugly in engagement with the adjacent end margin of the annular drum wall 47. The end wall 50 is provided with an outer peripheral portion 52 which extends outward from the drum wall 47 to the inner surface of the peripheral wall 16 of the heating roll and may be integral with inner flanged end wall portions 50, 51 which form a closure for the end of the drum. Or the inner end wall portion 52 may be in the form of an annular sheet or plate of sheet metal fitted to the end portion of the drum 47 and extending to the inner surface of the peripheral wall 16 of the roll 15 and to and, by preference, in engagement with the inner surface of the end wall 18 of the roll 15.

The outwardly projecting annular end wall 48 on or attached to the end margin of the annular wall or inner drum member 47, is dished or concave on its outer side which faces toward the outer end wall 17 of the roll, and is by preference bent to form an annular peripheral flange 52' which extends into engagement with the inner surface of the outer peripheral wall 16 of the roll and the inner surface of the end wall 17 at the inner periphery of the outer wall 16 of the roll; but the peripheral margin 53 is so formed as to provide a restricted space or opening 54 between said margin and the adjacent walls 16, 17 of the roll adapted to permit the escape of products of combustion from the combustion chamber 40 at the upper extremity of said chamber through the circumferential peripheral outlet opening or space 54 into the end chamber or space 55 and out through an upper outlet opening or openings 56 in and through the end wall 17 which is provided with one or more, preferably a series of such openings 56.

The outlet opening or openings 56 thus permit the escape of products of combustion from the end chamber 55 at a point or points above the level of the air inlet openings 57 in the hub 19 or end wall of the roll, and leading into the axial opening 41 and end chamber 55 of which said axial opening forms a part.

The outlet opening 56 at the highest point at which such openings occur, whether the uppermost outlet opening 56 is stationary or moves with the rotating end wall of the hollow heating and bending roll, is below the level of the upper extremity of the annular combustion chamber 40 on the inside of the roll 15 and below the level of the upper inner peripheral outlet opening or space 54 which is at the extreme upper margin of the combustion chamber 40. But the uppermost outlet opening 56 is above the level of the air inlet opening or openings 57. And in the form of the device in which the openings 56 are in the end wall of the hollow heating roll

which rotates, it is obvious that the lowermost one or more of the outlet openings 56 will act in the capacity of air inlet openings when below the level of the air inlet openings 57.

From the foregoing it will be seen that the heated gases and products of combustion are permitted to escape from the combustion chamber 40 at the upper extremity of said chamber, into the end chamber 55, but can only escape from the latter at a point or points below the level of the upper extremity of the combustion chamber 40, and above the level of the air inlet opening or openings to the end chamber 55. The heat is thus greatest at the upper extremity of the combustion chamber, where the peripheral wall of the heating and bending roll is in contact with and acts to heat and bend the metallic printing plate to be operated upon, and is not permitted to escape or be dissipated without first rising to the upper extremity of the heating or combustion chamber. The inner walls 48 and 52 are provided with suitable openings through which the burner tubes or pipes 45 extend. And it will be readily seen that the burner, including the branch pipes 45, and the inner drum 47 and inner end wall members 48, 50, 52 may remain stationary while the roll is rotated in the operation of heating and bending printing plates, although said burner and inner drum members and inner end walls may be permitted to rotate with the roll 15 if desired.

An annular bushing 58 which encircles the supply pipe 42 extends into the axial opening 41 and closes the same, forming a bearing around the pipe 42. The bushing 58 may be threaded and in threaded engagement with an inner threaded opening in the hub 19, if desired, and is provided with an annular flange 59 which has perforations 60 therethrough, each movable into and out of position to register with a corresponding air inlet opening 57 in the hub 19. A very simple and efficient means for controlling the air inlet openings 57 is thus provided. And it is obvious that the bushing may be caused to move longitudinally of its axis into and out of position to open or close all of the openings 57, if desired, or may be rotated so as to either partially or completely open or close any opening or openings 57 which are in position to register with the opening or openings 60 in the bushing 58.

I provide one or more auxiliary bending rolls 61 rotatively mounted in the frame of the machine in position to permit the metallic printing plate, backing sheet or sheets and intermediate sheets or material to pass between such roll or rolls 61 and the hollow heating and bending roll 15. Each roll 61 is rotatively mounted with its axis parallel to the axis of the hollow heating and bending roll 15, and is movable toward and from

the roll 15 to different desired or predetermined adjusted positions.

Each roll 61 is provided with an axle or trunnions 62 forming end journals at opposite ends of the roll which are journaled in adjustable or sliding bearing blocks 63 slidably mounted between parallel ways or guides 64, 64 formed by the upright standards 2 and 3 respectively adjacent to the opposite ends of the rolls 15 and 61, and adapted to guide the latter as it is moved to different adjusted positions.

Suitable means for adjusting the sliding blocks and thereby the roll or rolls 61 is provided, which may be of any desired ordinary and well known form. For example, each sliding block 63 is provided with an adjusting screw 65 non-rotatively mounted in or fixed to such sliding block and movable upward and downward with the block, the upper end portion of each screw 65 being screw-threaded. A toothed beveled gear 69 is mounted in screw-threaded engagement with each adjusting screw 65, and rotatively supported in a suitable bearing 66 in the corresponding side frame member or standard 2, or 3 as the case may be. Each of the beveled gears 69 has an annular collar 70 fixed to the lower end of the hub of the gear and adapted to abut against the under side of the bearing 66 so as to permit the rotation of the gear but prevent the movement of the same longitudinally of its axis.

A shaft 71 is rotatively mounted in suitable bearings 68, 68 in the frame; and bevelled gear wheels 72, 72 are fixed to the opposite ends of said shaft 71 and each in toothed engagement with an adjacent bevel gear 69 already described. A hand wheel or other suitable operating means 73 is mounted on or connected with the shaft 71 the rotation of which in one direction will cause the roll 61 to be raised. It follows as a matter of course that the rotation of the shaft 71 in an opposite direction will cause the roll 61 to be moved toward the roll 15 or lowered. The axes of the rolls 61 and 15 are thus at all times parallel; and heating and bending rolls of different or varying diameters may be used interchangeably, and the space between the rolls 61 and 15 may be regulated accurately and the roll or rolls 61 adjusted as desired.

The hollow heating and bending roll is provided with a peripheral printing-plate-engaging bar 74 which extends longitudinally of the roll and, by preference, from end to end thereof and in parallel relation to the axis of the roll.

This plate-holding strip or bar 74 is provided with a side flange 75 which projects over a corresponding inner longitudinal marginal notch or recess 76, which is adapted to receive and removably hold in position the corresponding adjacent marginal portion or

edge of a metallic printing plate, such as an electrotype or stereotype plate 77 to be heated and bent. The marginal flange 75 projects over the adjacent marginal portion of 5 the metallic printing plate and acts to removably but firmly hold said margin between the flange and the adjacent peripheral surface of the roll 15 during the operation of heating and bending the plate. An outer 10 flexible backing sheet or plate 78, which is by preference, made of flexible sheet metal, extends over the outside of the plate-holding bar 74 and from end to end of said bar, and has its forward edge secured to the peripheral surface of the heating and bending roll 15, or in engagement with the bar 74 and roll, in advance of the said bar by suitable securing means, such, for example, as a securing strip 74' riveted in place or otherwise 15 secured to the backing plate 78 and its support.

The flexible outer metallic backing plate or sheet 78 is of sufficient length to completely or approximately encircle the heating and bending roll on which it is mounted. 20 Any desired number of intermediate backing sheets of flexible material may be interposed between the outer metallic backing sheet 78, and the metallic printing plate to 25 be operated upon. For example intermediate sheets 79, 80, 81, 82 and 83, of suitable flexible material are, by preference, interposed between the printing surface of the metallic printing plate and said outer metallic backing sheet, as shown in Figs. 3 and 4. The sheet 81 which is in contact with the printing surface of the metallic printing plate is, by preference, formed of paper pulp or similar compressible material.

40 In operation, a metallic printing plate, such as an electrotype or stereotype plate, copper printing plate, zinc, or aluminum plate, or printing plate of any desired material, is provided and covered with a layer, 45 sheet or sheets of paper pulp or similar compressible material 81. Suitable intermediate sheets may then be interposed between the compressible sheet 81 and the outer metallic backing sheet, and the roll is then, by preference, heated, and all of said sheets including the metallic printing plate, are bent simultaneously, by rotating the heating and bending roll while said sheets are in position to pass between the bending rolls 15 and 61. 50 The bent printing plate and said sheets are then removed and the intermediate sheets discarded or used over again, as may be desired. And the operation is repeated in the heating and bending of other or similar metallic printing plates, as desired, using the same hollow heating and bending roll for as many successive operations as may be desired; or using hollow heating and bending rolls of different diameters or varying sizes 65 or curvatures interchangeably or as desired.

From the foregoing description it will be readily understood by those skilled in the art that hollow heating and bending rolls of different or varying diameters may be used interchangeably without disturbing or 70 changing the driving gears or worm and worm wheel mechanism, and whether the heating and bending rolls are of cylindrical form or partially cylindrical and partially flat or segmental. And the heating device 75 herein shown and described, is adapted to be used, with such modifications as will readily occur to a mechanic skilled in the art and familiar with the construction and operation of machines and methods of heating and 80 bending metallic printing plates, for heating hollow heating and bending rolls of other than completely cylindrical form, and whether such hollow heating and bending roll or rolls may be so mounted that their 85 axes are horizontal or vertical.

I have found in practice that in order to obtain the best and most satisfactory results the heating roll should be heated to a very high temperature, such as is not readily obtainable by other means than that of a burner, preferably a gas burner, inside of the roll; and that the compressible sheet material should be heated and compressed against the metallic printing plate while the 90 compressible material is in a moist or plastic condition; and that said compressible material should be not only heated and bent progressively simultaneously with and while in contact with the metallic printing plate, 95 but, by preference, also dried progressively and during the operation of heating and bending the metallic printing plate, and allowing the latter to cool and set, by preference, while held firmly in place upon the 100 heating and bending roll. Cooling to a temperature below that which is necessary to permit or cause the printing plate to set and hold its proper curvature, before removal from the roll is of course unnecessary. 105

I claim:

1. In a machine for heating and bending metallic printing plates, the combination of a plurality of parallel rolls including a horizontal rotative hollow heating and bending roll adapted to be interchanged with other similar rolls of different sizes, driving shaft and gear mechanism for rotating such interchangeable hollow heating and bending rolls of different sizes successively, means for 115 heating said hollow heating and bending rolls during the rotation thereof, stationary supporting means adapted to support said rolls in position to rotate upon horizontal axes, and connecting means adapted to detachably connect said driving shaft with each of a plurality of such interchangeable hollow heating and bending rolls successively and acting to permit the removal of any heating and bending roll so detachably con- 120

nected with said driving shaft independently of and without removing said driving shaft from its support.

2. In a machine for heating and bending metallic printing plates, the combination of a hollow heating and bending roll forming a combustion chamber having a discharge opening, a burner extending into the interior of such hollow roll, an inner hollow drum mounted inside of said roll and forming an annular partition wall between the combustion chamber and the axis of the roll and encircling said axis, means for supplying combustible fluid to said burner, an auxiliary roll rotatively mounted and having its axis in parallel relation to the axis of the hollow heating and bending roll and adapted to permit the passage of a metallic printing plate between the adjacent peripheries of said rolls, to be heated and bent, and means for rotating said rolls.

3. In a machine for heating and bending metallic printing plates, the combination of a hollow heating and bending roll forming the outer peripheral wall of a heating chamber located within the roll, an inner hollow drum located inside of said roll and forming an inner wall of said heating chamber, a burner for heating said chamber, means for supplying fuel to said burner, a driving shaft rotatively mounted independently of said roll, for rotating the same, means for rotatively supporting said hollow heating and bending roll independently of and normally out of engagement with said driving mechanism, and means for detachably connecting said driving shaft with the roll and adapted to permit the removal of the roll from its support independently of and without removing the driving shaft from its support.

4. In a machine for heating and bending metallic printing plates, the combination of a hollow heating and bending roll forming an outer peripheral wall of a combustion chamber located within the roll, a support for said roll, an inner hollow drum located inside of said roll and forming an inner wall of said heating chamber, a burner located inside of said roll, for heating said chamber and the periphery of the roll, a fuel supply pipe extending into the end of said roll and connected with said burner, and means for detachably connecting said roll with a source of power.

5. In a machine for heating and bending metallic printing plates, the combination of a hollow heating and bending roll forming an outer peripheral wall of a combustion chamber located inside of the roll, an inner drum located inside of said roll and forming an inner wall of said combustion chamber, an inner end wall extending between the outer end wall of the roll and the combustion chamber and forming an end chamber inside

of the roll, an air inlet leading into said end chamber, an outlet leading from the upper portion of the combustion chamber, means for admitting air from the end chamber into the combustion chamber, a burner extending into the combustion chamber, and means for supplying fuel to said burner.

6. In a machine for heating and bending metallic printing plates, the combination of a hollow heating and bending roll forming an outer peripheral wall of a combustion chamber and having end walls, an inner drum located inside of said roll and forming an inner wall of said combustion chamber, an inner end wall extending between the outer end wall of the roll and the combustion chamber and forming an end chamber having air inlet and outlet openings, said inner end wall having a space between its upper extremity and the upper peripheral wall of the roll for permitting the escape of gaseous fluid from the combustion chamber, means for admitting air to the combustion chamber, a burner extending into the combustion chamber, and means for supplying fuel to said burner.

7. In a machine for heating and bending metallic printing plates, the combination of a hollow heating and bending roll forming a combustion chamber, an inner end wall extending between the outer end wall of the roll and the combustion chamber and forming an end chamber having air inlet and outlet openings, a discharge opening leading from the upper portion of the combustion chamber into said end chamber, means for admitting air into the combustion chamber at a point located below the level of said discharge opening from the combustion chamber, a burner extending into said combustion chamber, means for supplying fuel to said burner, and means for rotating the hollow heating and bending roll.

8. In a machine for heating and bending metallic printing plates, the combination of a hollow heating and bending roll provided with an annular inner combustion chamber, an inner end wall extending between the outer end wall of the roll and the combustion chamber and forming an end chamber having an outlet opening and an air inlet opening, a discharge opening located above the level of said outlet opening and leading from the combustion chamber into the end chamber, means for admitting air into the combustion chamber, a burner for heating the combustion chamber, and means for supplying fuel to the burner.

9. In a machine for heating and bending metallic printing plates, the combination of a hollow heating and bending roll provided with an inner annular combustion chamber and having end walls, an inner end wall extending between the outer end wall of the roll and the combustion chamber and form-

ing an end chamber having inlet and outlet openings leading to the outside of the roll, an outlet opening leading from the upper part of the combustion chamber into said end chamber at a point above the level of said outlet opening in the end chamber, an air inlet opening for admitting air to the interior of the combustion chamber, a burner extending into the combustion chamber, and 10 means for supplying fuel to the burner.

10. In a machine for heating and bending metallic printing plates, the combination of a hollow heating and bending roll forming an annular combustion chamber having 15 outer and inner annular walls and provided with air inlet and gas outlet openings for said combustion chamber, end walls for said roll, an inner end wall extending between the outer end wall of the roll and said combustion chamber and forming an end cham- 20

ber having inlet and outlet openings leading to the outside of the roll, a gas burner extending into the combustion chamber, a fuel supply conduit extending into the roll and connected with said burner, means for rotatively supporting said roll, a driving shaft located adjacent to the opposite end of the roll from said end chamber, means for rotatively supporting said driving shaft independently of the roll, and means for detachably connecting the roll with the driving shaft and adapted to permit the removal of the roll from its support independently of and without removing the driving shaft from its support. 25 30 35

Signed at Chicago, in the county of Cook and State of Illinois this 21st day of April, 1924.

CHRISTIAN N. SMITH.
